Fig. 1

Fig. 2

Fig. 3

FIG. 4

FIG. 1 is a perspective view of a tire showing the new design, it being understood that the tread pattern shown is repeated throughout the circumference of the tire, and the opposite side of the tire has the illustrated design in the shoulder area only and is otherwise of conventional design without the illustrated sidewall pattern of concentric white and black rings;

FIG. 2 is an enlarged fragmentary top plan view of a portion of the tire shown in FIG. 1;

FIG. 3 is a fragmentary transverse sectional view through the tire substantially on the plane indicated by the line 3—3 of FIG. 2; and

FIG. 4 is a side view of the tire as viewed from the right in FIG. 1, it being understood that the full line por-

tion of the sidewall is repeated throughout the circumference of the tire indicated by the dot-dash lines.

I claim:

The ornamental design for a tire, substantially as shown and described.
